UNITED STATES PATENT OFFICE.

EDWARD RAYMOND-BARKER, OF WIMBLEDON, ENGLAND, ASSIGNOR TO COMMERCIAL CABLE COMPANY, OF NEW YORK, N. Y., A CORPORATION OF NEW YORK.

TELEGRAPH TRANSMITTING SYSTEM.

1,119,117.

Specification of Letters Patent.

Patented Dec. 1, 1914.

Application filed July 18, 1912. Serial No. 710,190.

To all whom it may concern:

Be it known that I, EDWARD RAYMOND-BARKER, a subject of the King of Great Britain, and a resident of 13 Lingfield road, 5 Wimbledon, Surrey, England, have invented certain new and useful Improvements in Telegraph Transmitting Systems, of which the following is a specification.

This invention relates to improvements 10 in electro-mechanical devices for sending electric currents into a submarine cable or other telegraph line under peculiarly advantageous conditions in regard to the electrical condition of the line; and it has for 15 its main object to provide means whereby a constantly alternating series of positive and negative current impulses may be sent to the line, each impulse constituting a signal unit, as a dot or a dash, so that no two following signal unit impulses will be of the same 20 polarity.

A further object of the invention is to provide electro-mechanical devices by means of which Morse signals of short dots and 25 long dashes controlled at the sending end of a cable or other telegraph line by an ordinary Morse key or by the ordinary form of Wheatstone automatic transmitter, may be sent into a cable by means of regularly alternating 30 positive and negative currents derived from a galvanic battery or other source of current, the said alternation always taking place whether the complete signals consist of a number of Morse dots in succession 35 or a number of Morse dashes in succession or a combination of Morse dots and dashes as met with in the various Morse codes.

A further object of the invention is to provide means at the receiving end of the line 40 to receive said alternating series of signal impulses without regard to their polarity and to reproduce them as Morse signal units, the dots and dashes being distinguished from each other by reason of their duration and 45 irrespective of the polarity of the current impulses.

Other important objects and advantages of the invention will appear hereinafter.

In the drawings, Figure 1 is a diagrammatic view of one form of my invention showing both the transmitting and receiving end of a cable system; and Fig. 2 a similar diagrammatic view showing a slightly different form of transmitting apparatus.

Fig. 3 is a detail view of the current changing disks.

Referring to the various parts by numerals, 1 designates a Morse hand key which works in and controls a local circuit containing a battery 2. In this local circuit is a 60 magnet 3 which is arranged to operate the arm 4 of a pole-alternator. This pole-alternator may be of any suitable construction, but as shown in Fig. 1 it consists of the electric magnet 3; the pivoted arm 4 carrying the magnet armature 5. On the end of the arm 4 is stiffly pivoted a depending tongue 6 which is pointed at its lower end and enlarged at its pivoted end. Below this tongue is pivoted a rocking beam 7. This rocking beam is so shaped, and is so adjusted in its position relative to the pointed tongue actuated by the pole-alternator that in any normal position of rest the point of the tongue cannot impinge upon the center of 75 the rocking beam but only at points near the center but on the one side or the other thereof. To accomplish this the rocking beam is provided with a central upwardly extending V-shaped tooth and with a corresponding tooth on each side of said center tooth, the pointed tongue engaging first on one side of the center tooth and then on the other side according to which side is uppermost when the tongue is making its downward stroke. A spring 8 engages the upper surface of the pivoted tongue and holds it normally in its vertical central position, as shown in Fig. 1, said tongue in its said central position being arranged to engage on 80 the right hand surface of the central tooth of the rocking beam. It is manifest that when the pivoted tongue makes its downward stroke the said tongue and rocking beam will be thrown to the right. When the 85 pivoted tongue moves upwardly it will return to its normal central position while the rocking beam remains in the position in which it was placed by the tongue. The result is that on the next downward stroke 100 of the tongue it engages the rocking beam on the left hand side of the central tooth and the said rocking beam and tongue will then be thrown to the left, and so on throughout each operation of the pole-alternator. From this it follows that successive workings of the pole-alternator armature 105 cause the pointed tongue to force the rock-

ing beam alternately to the right and to the left and the tongue is deflected away from its central position either to the right or to the left. This vibratory or swinging movement of the tongue I make use of to alternately close two local circuits in each of which, actuated by a common local battery, is an electro-magnetic transmitter. These two transmitters, in conjunction with a sending battery, act as an ordinary cable key capable of sending either positive or negative currents to the line.

Projecting at right angles from the face of the tongue 6 is an arm 9 which is adapted to engage one or the other of two contact points 10 and 11 each of which is in an independent local circuit. The arm 9 is in circuit with the batteries of said local circuits so that said arm completes one or the other of said circuits upon each downward movement of the arm of the pole alternator. In each local circuit is an electro-magnet 12 each of said magnets forming a part of a transmitting device 13 and 14. A pivoted arm 13^a of the transmitting device 13 operates between two contact points 15 and 16 while a corresponding arm 17 of the transmitter 14 operates between two contacts 18 and 19. It is, therefore, manifest that the contact arm 9 will first close the local circuit through the transmitter 13 and upon its next operation will close the circuit through the transmitter 14. The transmitter 13 is arranged to place negative current to the line or cable and the transmitter 14 is arranged to place positive current to the line or cable. To accomplish this the back contacts 15 and 18 of the two transmitters are connected to the positive pole of the battery or other source of electric current and the front contacts 16 and 19 are connected to the negative pole of the battery or other source of electric supply. The armature of the transmitter 13 is electrically connected to the cable or telegraph line C by wire c, while the armature of the transmitter 14 is connected to earth at E. It is manifest from this arrangement that when the arm of transmitter 13 is actuated and thrown against its front stop 16 a negative impulse will be sent to the line, and when the corresponding arm of the transmitter 14 is actuated and its pole-changing arm sent against its front contact 19 a positive impulse will be sent to the line. It is clear that the alternations of current impulses to the line take place automatically on the operation of the transmitting key or other transmitting apparatus and that said transmitting apparatus or device is operated in the ordinary manner for transmitting Morse characters. Successive workings of the pole-alternator armature cause alternate positive and negative currents to pass to the line irrespective of the length or time value of each current impulse.

At the receiving end of the cable any suitable form of receiving device may be employed, such, for instance, as a relay 20 having a swinging tongue 21 adapted to be moved in response to the incoming currents. This relay is provided with two stops 22 both of which are connected to one side of any suitable form of non-polarized relay or Morse receiving instrument 23, the contact of the relay 20 being connected to said instrument through a local battery. It is manifest that the signal impulses will be reproduced in the receiving instrument as short or long impulses irrespective of the polarity of the impulses, said signal impulses being distinguished from each other by the time or length of duration.

In the form of apparatus shown in Fig. 2 a hand Morse key 24 is arranged in a local circuit which includes an electro-magnet 25 of an electro-mechanical cable key or transmitting device 26. This key is provided with a pivoted arm 27 which carries the armature for the electro-magnet 25. One end of this arm carries a contact point 28 which vibrates between a back stop 29 and a front stop 30. The swinging arm of the transmitting device is electrically connected to the cable or telegraph line C, and the back stop of said transmitting device is connected to earth. One end of the arm 27 is adapted to engage the teeth of a ratchet wheel 31, said arm and said wheel being so arranged that upon each operation of the arm the wheel will be rotated one tooth so that said wheel has an intermittent step-by-step rotary movement under the influence of the transmitting device operated through the Morse transmitting key. On the shaft 31^a of the ratchet wheel are secured two disks 32 and 33 of any suitable non-conducting material. Each disk carries a contact point for each tooth of the ratchet wheel. As shown in the drawing the ratchet wheel has eight teeth and the contact or circuit closing disks each have eight contact points 34. These contact points are electrically connected to a sending battery 35, each alternate point being connected to the positive pole of the battery, the other points being connected to the negative pole of the battery; and the said contact points are so arranged on each disk that a negative contact point of one disk will be adjacent to and in line with a positive contact point on the adjacent disk. Adapted to engage these contact points are two contact brushes 36 and 37, the brush 36 engaging the points of circuit closing disk 32 and the brush 37 engaging the contact points of disk 33. This latter brush 37 is electrically connected to earth while brush 36 is connected to the front stop of the transmitting key.

It is manifest from the arrangement of the parts shown in Fig. 2 that upon the de-

pression of the Morse transmitting key the ratchet wheel and the circuit closing disks will be given a rotary movement sufficient to shift the contact under the brushes and thus change the polarity of the current to the line, the contact point of the transmitting key at the same time engaging its front contact so that the brush of circuit closer disk 32 will be directly connected electrically to the cable. Therefore, as the brush of said disk will alternately engage positive and negative contact points, the polarity of the current of the line is changed at each operation of the Morse key. The circuit closer disk 33 correspondingly puts positive or negative current to earth.

The receiving apparatus for the form of transmitter shown in Fig. 2 is precisely the same as that used in connection with the apparatus shown in Fig. 1.

From the foregoing it is clear that I provide very simple electro-mechanical means for transmitting signals made up of dots and dashes, said signals being transmitted by means of alternating impulses of current of opposite polarity.

Many modifications of the mechanical means for securing the reversals of current may be employed and I do not wish to be limited in this respect; and the system may be duplexed in the ordinary manner, if desired.

I am aware that the broad principle of a telegraph system wherein the signals or units of signals are transmitted by a series of electric impulses in which each impulse is opposite in polarity to the preceding one, so that no two following or successive signal impulses are of the same polarity, is the invention of John Gott of Brighton, England, for which invention he has made application for patent, and I do not wish to claim said principle or telegraph system, broadly.

What I do claim as my invention and desire to secure by Letters Patent, is:

1. A system of electric signaling comprising a transmitting key, a line, means for throwing upon the line impulses of current each impulse constituting a signal unit, said means earthing the line after each current impulse, and mechanically operated means controlled by the closure of the key for reversing the polarity of the current to the line for each signal unit impulse.

2. A system of electric signaling comprising a signal transmitting means, a line, means for throwing upon the line impulses of current, each impulse constituting a signal unit, said means earthing the line after each current impulse, and mechanically operated means controlled by the closure of the transmitting means for reversing the

polarity of the current to the line for each signal unit impulse.

3. A system of electric signaling comprising a signal transmitting apparatus, a line, means for throwing upon the line impulses of current, each impulse constituting a signal unit, said means earthing the line after each current impulse, and mechanically operated means controlled by the closure of the signal transmitting apparatus for reversing the polarity of the current to the line for each signal unit impulse, whereby no two following signal unit impulses will be of the same polarity.

4. A system of electric signaling comprising a signal transmitting apparatus, a line, means for throwing upon the line an impulse of current for each closure of the signal transmitting apparatus, each impulse constituting a signal unit, a circuit reverser controlled by the closure of the transmitting apparatus to change the polarity of the line current for each succeeding impulse of current and means for earthing the line after each current impulse.

5. A telegraph system comprising a line, means for throwing positive or negative current to the line, a transmitting device, an electro-mechanical means for controlling the polarity of the current to the line, said means reversing the polarity to the line at each successive operation, means at the receiving end of the line responsive to impulses of current of opposite polarity, and means to reproduce said impulses irrespective of their polarity, whereby said reproduced impulses can be distinguished from each other only by their duration or length, and irrespective of their polarity.

6. A system of electric signaling comprising a transmitting means, a line, means for throwing upon the line impulses of current each impulse constituting a complete signal unit, said means earthing the line after each current impulse, mechanically operated means controlled by the transmitting means for reversing the polarity of the current to the line for each signal unit, means at the receiving end of the line responsive to impulses of current of opposite polarity and means to reproduce said impulses as signals irrespective of their polarity, whereby said reproduced signal impulses can be distinguished from each other only by their duration or length and irrespective of their polarity.

In testimony whereof I hereunto affix my signature in the presence of two witnesses.

EDWARD RAYMOND-BARKER.
